C. L. CRAINE

ARCH SUPPORT

Filed Aug. 7, 1922

Fig. 5-

Inventor
Charles L. Craine
By H. Z. Lord
Attorney

UNITED STATES PATENT OFFICE.

CHARLES L. CRAINE, OF MEADVILLE, PENNSYLVANIA, ASSIGNOR OF ONE-HALF TO
EDWARD C. SMITH, OF MEADVILLE, PENNSYLVANIA.

ARCH SUPPORT.

Application filed August 7, 1922. Serial No. 580,043.

To all whom it may concern:

Be it known that I, CHARLES L. CRAINE, a citizen of the United States, residing at Meadville, in the county of Crawford and

5 State of Pennsylvania, have invented new and useful Improvements in Arch Supports, of which the following is a specification.

This invention is designed to improve arch supports. Such supports must have 10 sufficient rigidity or supporting quality to carry the arch. At the same time they must conform to the local variations encountered in arches to distribute the support. In accomplishing this I utilize a series of wire 15 arched members preferably of round, or wire having equal cross dimensions which wires are rigidly connected by welding or otherwise with the end plates, the rigid connection with the end plates retaining the 20 wires in their arched form and in proper relation to each other and forming a means to which the pad covering the arched wires may be permanently secured. It is also desirable to provide such a device with means 25 for supporting the metatarsal depression and to have this support adjustable to fit different conditions. Other features of the invention will appear from the specification and claim.

30 The invention is illustrated in the accompanying drawings as follows:—

Fig. 1 shows a section of the support on the line 1—1 in Fig. 2.

Fig. 2 a bottom view of the support.

35 Fig. 3 a section on the line 3—3 in Fig. 1.

Fig. 4 a side elevation of the filler forming the local metatarsal support.

Fig. 5 a bottom view of the filler.

1 marks the rear end plate and 2 the front 40 end plate. These are connected by the wires 3, the ends of which are rigidly secured by electric welding, or otherwise to the plates 1 and 2. These wires form the arch as clearly shown in Fig. 1 and are so arranged as to 45 be properly spaced across the support. The wires are preferably of approximately equal

cross dimensions ordinarily of round wire so as to readily flex not only in the direction of the arch but slightly sidewise if necessary to conform to the shape of the arch of the 50 foot. On the other hand the rigid connection with the plates assures the holding of the wire so that it directs its supporting force upwardly, in other words, it prevents the wires turning and thus yielding without 55 giving the proper support.

The pad 4 conforms to the general shape of the arch and is supported to at least one of the plates by rivets 5. It has the usual side support 6. Efforts have heretofore 60 been made to secure such pads by means of cements and otherwise but difficulty has been encountered as to this by reason of the heat, wear and moisture to which the pad is subjected.

65 The front plate 2 has a transverse slot 7 into which the tongue 8 of the filler 9 extends. This filler is arranged under the pad 4 and forms a local arch 10 for the metatarsal depression. The filler may be shifted 70 crosswise along the slot 7 so that it may be made to conform to the foot of the wearer. This filler may be made of any desirable material such as rubber or aluminum.

The rear plate 1 is provided with an opening 11 into which the pad 4 is depressed. This forms an oscalsis depression in the pad.

I prefer to provide the pad with openings 12 which being over the open wires 3 and these wires being spaced ordinarily from 80 the bottom of the shoe give ample ventilation to the foot.

What I claim as new is:—

In an arch support, the combination of 85 end metallic plates; and a series of connecting resilient wires of arched form extending between the plates and rigidly connected thereto.

In testimony whereof I have hereunto set my hand.

CHARLES L. CRAINE.
